UNITED STATES PATENT OFFICE.

JOHN HAYS HAMMOND, JR., OF GLOUCESTER, MASSACHUSETTS.

SYSTEM OF MULTIPLE CONTROL.

1,239,592.

Specification of Letters Patent. Patented Sept. 11, 1917.

Application filed December 30, 1909, Serial No. 535,626. Renewed May 28, 1913. Serial No. 770,523.

To all whom it may concern:

Be it known that I, JOHN HAYS HAMMOND, Jr., a citizen of the United States, residing at Gloucester, in the State of Massachusetts, have invented certain new and useful Improvements in Systems of Multiple Control, of which the following is a specification, reference being had to the accompanying drawings, forming a part hereof.

10 The object of my invention is to provide a system whereby a variable number of operating mechanisms may be definitely and absolutely controlled by wireless impulses from a single sending station, and the invention consists in the new and novel features of construction and combinations of parts hereinafter set forth and claimed.

In the accompanying drawings

Figure 1 is a diagrammatic view in side elevation of an apparatus embodying my invention.

Fig. 2 is a diagrammatic plan view of the same apparatus.

A wireless impulse may be sent from any suitable sending station located at a distance from the control mechanism. The impulses are received by any suitable receiving means as an antenna 1 connected with a coherer or similar device 2 in circuit with a relay magnet 3 and the battery 4. The armature of the relay controls a switch 5 in circuit with a magnet 6, the armature 7 of which controls a switch 8 in circuit with the main or prime motor 9 and main battery 10. The main controller 11 is operatively connected with the motor by any suitable means, as a clutch (not shown) and is provided with a plurality of contacts 12 and neutral spaces 13. The periphery of the controller drum 14 is preferably provided with a plurality of stops or notches 15, one of said notches corresponding to each set of contacts and each neutral space and adapted to be engaged by any suitable means as a catch 16 provided upon a suitable lever arm 17 operated by the armature of the magnet 6. A switch 18 is interposed in the circuit from each set of contacts, said switch being controlled by a centrifugal governor 19 upon the shaft of the main motor and so constructed that the switch will be closed only when the motor slows down preparatory to stopping, and will afterward be opened again. These switches can be so constructed that they will remain closed long enough to cause the tertiary controllers to be operated, and they and the secondary controllers are so designed that the circuits to the tertiary controllers are not closed when the secondary motors are started. As many secondary

that it will remain closed long enough to 55 cause the secondary controllers to be operated, and it and the primary controller are so designed that the circuits to the secondary controllers are not closed when the main motor is started. 60

It will thus be seen that upon the sending of an impulse from the sending station it will be received by the antenna and through the connections heretofore described will cause the main motor to operate which in 65 turn will rotate the controller. In case the impulse is a short one the controller will rotate only one notch because, upon the cessation of the sending impulse the armature of the operating magnet will be released, thus permitting the lever arm to engage with the next succeeding stop or notch. In case, however, the impulse is continuous the controller will continue to rotate as the lever arm will be held out of engagement 70 with the stops and consequently the controller can be caused to make one or more complete revolutions if desired. When the catch or hook seats in one of the stops or notches the circuit of the main motor is 75 broken and when said main motor slows down the switch 18 is closed thus energizing the motor connected with the secondary controller as hereinafter described.

Each set of contacts 12 is in circuit with 85 a secondary operating magnet 21, the armature of which controls a switch 22 in circuit with a secondary motor 23. Said motor rotates a secondary controller 24 having a plurality of contacts 25 and neutral spaces 26. 90 The drum 27 of the controller is provided with a plurality of stops or notches 28 adapted to be engaged by a catch or hook 29 operated by the armature of the magnet 21. A switch 30 is provided in the circuit from each set of contacts, said switch being operated by a centrifugal governor 31 upon the shaft of the secondary motor so arranged that the switch will be closed only when the motor slows down preparatory to stopping, and will afterward be opened again. 95 These switches can be so constructed that they will remain closed long enough to cause the tertiary controllers to be operated, and they and the secondary controllers are so designed that the circuits to the tertiary controllers are not closed when the secondary motors are started. As many secondary

motors and controllers may be employed as there are sets of contacts provided upon the main controller.

When the main controller has been actuated so as to bring one set of contact fingers into connection with one of the secondary motors and the operation of the controller and motor is then stopped, the slowing down of the main motor will close the switch 18 thereby energizing the secondary magnet 21 and closing the circuit of the secondary motor. The operation of the motor actuates the secondary controller and moves the notch out of registry with the hook or catch 29. Consequently, although the main circuit through the switch 18 is broken, the local circuit through the switch 22 is held closed by drum 27 and remains closed until the secondary controller has rotated at least one notch. In order to actuate the secondary controller so as to move same an additional notch it is necessary to cause the main controller to make one complete revolution.

Each set of contacts 25 on the secondary controller is in circuit through the contact fingers 33 with a tertiary operating magnet 34, the armature of which controls a switch 35 in local circuit with the tertiary motor 36. Said local circuit comprises a switch 37 in which one of the switch members, preferably formed by a sleeve 38, is actuated by a centrifugal governor 39 on the shaft of the prime or main motor 9 and so constructed and arranged that said circuit will be closed only when the main motor is absolutely at rest. Each of said motors 36 rotates a tertiary controller 40 provided with a plurality of contacts 41 and neutral spaces 42. The drum of each controller is provided with a plurality of stops or notches 43, one of said stops or notches corresponding to each set of contacts and each neutral space on the controller. A catch or hook 44 operated by the armature of the magnet 34 is adapted to engage with said stops or notches. Each set of contacts may be in circuit with a driving motor 45 connected through suitable gearing 46 with any desired mechanism.

When any one of the secondary controllers is rotated so as to bring one of the sets of contacts thereon into engagement with the contact fingers connected with one of the tertiary motors the catch of the secondary controller in falling into the notch breaks the circuit through the secondary motor and the slowing down of the secondary motor closes the switch 30. Meanwhile the main motor has come to an absolute rest during the period that the secondary controller is traversing the arc from one notch to the next succeeding notch so that the switch 37 is also closed, thus releasing the tertiary catch, starting the tertiary motor

and bringing the notch on the tertiary drum out of register with the hook or catch 44. Consequently the tertiary controller will rotate until the hook or catch seats in the next succeeding notch. No switches are provided in the local circuit connecting the tertiary controller with the operating or quaternary motor 45 and as soon as the contacts on the tertiary controller engage with the contact fingers connected with said motor it will operate and continue to operate until the tertiary motor is rotated to its neutral position. The switch 37 prevents any interference with the operation of the tertiary series of motors except when the secondary controller is in operative relation thereto.

Although only one of the secondary motors is illustrated in the drawing as connected with a series of tertiary motors it is obvious that each of the secondary motors shown may also be connected to a series of tertiary motors, and that these in turn may be connected to a plurality of driving motors. By means of this construction a large number of mechanisms may be controlled from a single sending station and through a single main controller, and the duration of the operation of each unit of the apparatus is constantly under the control of the operator. It will be obvious that various changes within the skill of the mechanic may be made in the mechanism herein shown and described without departing from the spirit of the invention, provided the means set forth in the following claims be employed.

I claim as my invention:

1. A system of multiple control comprising a main controller, a plurality of subsidiary controllers in local circuits, a switch in each of said local circuits, means to operate said switches intermittently to close said local circuits, said subsidiary controllers having individual means operatively connected therewith for permitting a predetermined movement and limiting said movement.

2. A system of multiple control comprising a main motor and controller in a main circuit, means for closing said circuit by wireless impulse, means permitting a predetermined limited movement of said main controller, a plurality of secondary motors and controllers in separate local circuits with the main controller and a switch in said local circuits adapted to be opened and closed by said motor, said secondary controllers including means permitting a predetermined movement of each of said secondary controllers and limiting the movement thereof, a plurality of tertiary controllers in separate local circuits with each secondary controller and a switch in said local circuits adapted to be opened and closed by said sec-

ondary motor, said tertiary controllers including means permitting a predetermined limited movement of each of said tertiary controllers, and an operating mechanism in 5 a local circuit opened and closed by said tertiary controller.

3. A system of multiple control comprising a main motor and a controller, a plurality of secondary controllers each in a 10 local circuit, a plurality of tertiary controllers each in a separate local circuit, a switch in each of said tertiary circuits adapted to be opened and closed by one of the subsidiary controllers, said main motor 15 being adapted to be energized by wireless impulses, a switch in each of said secondary local circuits adapted to be opened and closed by said motor, and a separate switch in each of said tertiary circuits adapted to 20 be operated by said motor.

4. A system of multiple control comprising a main controller, a motor for operating said controller adapted to be energized by wireless impulses, a secondary motor and 25 controller in a local circuit, a switch in said local circuit governed by the main motor, a tertiary controller in a local circuit, a switch in said local circuit governed by the secondary motor, a separate switch in said 30 local circuit, and independent means for governing said switch independently of the main or secondary controllers.

5. A system of multiple control comprising a main controller and motor for rotating the same, a secondary controller in circuit with the main controller, a tertiary controller in circuit with the secondary controller, and a switch in circuit of said tertiary controller controlled by said main 40 motor.

6. The combination with a motor of means to inaugurate the operation of said motor,

and means controlled by said motor and automatically operative to cause a continuation of the operation of said motor for a predetermined and limited period independently of said first mentioned means. 45

7. The combination with a rotary shaft of a contact arranged to reciprocate longitudinally thereof, means whereby said contact is caused to move longitudinally of said shaft at a rate depending upon the rate of rotation of said shaft, and a contact arranged normally in the path of but out of engagement with said first mentioned contact and arranged to be engaged by said first mentioned contact when said shaft is rotated at a predetermined rate. 50

8. The combination with a motor, of means responsive to radiant energy to inaugurate the operation of said motor, and means controlled by said motor and automatically operative to cause a continuation of the operation of said motor for a predetermined and limited period independently of said first mentioned means. 55

9. A system of multiple control comprising a main controller arranged to be actuated in response to radiant energy, a plurality of subsidiary controllers arranged to be initially actuated selectively as a result of the action of said main controller, and means associated with each of said subsidiary controllers and controlled thereby for causing a continuation of the operation 60 of each of said subsidiary controllers for a predetermined and limited period independently of said main controller. 70

This specification signed and witnessed this 16th day of December, A. D. 1909.
